[57] **CLAIM**

The ornamental design for a rifle with two barrels, substantially as shown and described.

DESCRIPTION

FIG. 1 is a side elevation view of a rifle with two barrels showing my new design;

FIG. 2 is a front elevation view thereof;

FIG. 3 is a top plan view thereof;

FIG. 4 is a rear elevation view thereof; and

FIG. 5 is a bottom plan view thereof.

The appearance of the rifle from the other side is the same as that in FIG. 1.

FIG. 1

FIG. 2

FIG. 3

FIG. 4

FIG. 5
